D. D. DALL

GOLF PRACTICE DEVICE

Filed May 31, 1923

INVENTOR,
David Dewar Dall
BY *Frederick C. Bromley*
ATTY.

UNITED STATES PATENT OFFICE.

DAVID DEWAR DALL, OF TORONTO, ONTARIO, CANADA.

GOLF-PRACTICE DEVICE.

Application filed May 31, 1923. Serial No. 642,716.

To all whom it may concern:

Be it known that I, DAVID DEWAR DALL, a subject of the King of Great Britain, residing at 185 St. Clarens Avenue, in the 5 city of Toronto, Province of Ontario, Dominion of Canada, have invented certain new and useful Improvements in Golf-Practice Devices, of which the following is a specification.

- 10 The invention relates to improvements in golf recording and exercising device as described in the present specification and shown in the accompanying drawing that forms part of the same.
- 15 The invention appertains to a device whereby the magnitude of the driving force of a golf player is recorded by a registering machine through its connections with a tethered golf-ball.
- 20 This device has for its object the exercising and improving of golf ability and can be competitively used by two or more players by comparison of their individual score records; furthermore is adapted for use 25 within limited spaces either in or out-of-doors and does not require to be secured during its usage.

Referring to the drawing, Figure 1 is a side elevation of the device.

30 Figure 2 is a top plan view.

Figure 3 is a central, vertical sectional view.

Figure 4 is a transverse sectional view taken on the line 5—5 of Figure 2.

35 Like numerals of reference indicate corresponding parts in each figure.

In the drawing, 1 designates the case or frame of the registering machine comprising a substantial rectangular base 2 having 40 inclined sides 3 rising therefrom to a top 4, said top sloping rearwardly obtusely so as to lie about parallel to the path of the ball in motion; the rear portion being cut away to constitute an opening therethrough 45 as at 5.

Formed in the top thereof is a ratch slide-way 6 extending longitudinally thereof and being rectangular in cross section and subjacent thereto is a click housing 7 substantially strengthened by integral webs, the housing being bored with a constriction 50 forming a shoulder to constitute a spring seat as at 8.

9 is a graduated ratch disposed with its 55 teeth face downward in the slide-way 6 and passing through a click 10 operatively

arranged in the housing 7, the teeth thereof being engageable with the teeth of said ratch for the purpose of precluding reverse movement, the top end of which click 60 is neatly rounded off as at 11.

Positioned in the housing bore, and shoudered between the constriction thereof and the click, is a compression spring 12 which is adapted to exert a pressure upon 65 the latter to hold it in engagement with the ratch.

13 is an extension spring secured at one end to the rear of the case, the other end being secured to the bifurcated terminus 70 of the ratch, and is provided for the purpose of restraining the outward movement of said ratch.

14 is a cover-plate detachably secured by means of screws to the case top 4 and 75 provided with a slot to receive the protruding end 11 of the click 10. The front edge 15 of the cover-plate serves as a mark for reading the graduations of the ratch, such reading being zero in the normal position 80 of the ratch. The graduations being preferably spaced a distance corresponding to the pitch of the teeth so that as each tooth advances over the click a corresponding graduation will register with said front 85 edges 15 of the top-plate thereby recording the magnitude of the pull upon the ratch.

In order to encase the mechanism as much as possible a bottom plate 16 is provided, detachably secured by screws or 90 otherwise fastened as may be found desirable.

17 are pads affixed to the underside of the base-plate, preferably constructed of rubber to create friction when engaged 95 with a support, thus imparting rigidity to the device in usage.

18 is a golf-ball connected to the tether 19 of suitable length which in turn is connected to the bifurcated extremity of the 100 ratch, such connection comprising securing of the tether around the pulley 20 which is rotatably disposed between the members of said bifurcated end, thus permitting freedom of movement of said tether. 105

In the operation of this device, the ball is situated about the length of the tether to the rear of the machine. The player then strikes the ball propelling same in the direction of the machine; the momentum of 110 the ball due to the driving force of the player is dissipated in drawing out the ratch

against its spring pressure, whilst the retraction of the ratch is prevented by the click engaging in the teeth thereof.

The magnitude of the driving force is indicated by the degree coinciding with the front edge of the plate through the withdrawal of the ratch. To retract the ratch it is merely necessary to depress the protruding end 11 of the click 10.

10 What I claim is:—

1. In a device of the class described, a case, friction pads affixed to its bottom, a graduated ratch slidably in said case, a tension spring secured to said ratch and to said case, a spring-pressed click disposed in the case and engaging the ratch teeth to retain the ratch in an extended position, means cooperating with the graduation upon the ratch to indicate its extended position, a tether, a golf ball, said tether being secured to the ratch and golf ball.

2. In a device of the class described, a case comprising a substantial rectangular

base, friction pads affixed to its bottom, inclined sides, a rearwardly sloping top, such sides rising from said base to meet said top, a slideway formed in said top, a graduated ratch slidably mounted in said slideway, a tension spring secured to said ratch and to said case top, a click housing formed integral with said case top subjacent said slideway and having a constricted bore, a spring and click mounted in said constricted bore, the click being pressed by the spring into engagement with the ratch teeth to retain the ratch in an extended position, means cooperating with the graduation upon the ratch to indicate its extended position, a tether, a golf ball, said tether being secured to the ratch and golf ball.

Signed at Toronto, Ontario, Canada, this twenty-ninth (29th) day of May, 1923.

DAVID DEWAR DALL.
